Primary Examiner — T Chase Nelson*Assistant Examiner* — Rachel Wolfe(74) *Attorney, Agent, or Firm* — Michael D. Lazzara; Leech Tishman Fuscaldo & Lampl(57) **CLAIM**

The ornamental design for a LED housing, as shown and described.

DESCRIPTION

FIG. 1 is a top three-dimensional view of the LED housing; FIG. 2 is a bottom three-dimensional view of the LED housing;

FIG. 3 is a right end elevational view of the LED housing; FIG. 4 is a left end elevational view of the LED housing; FIG. 5 is a left side elevational view of the LED housing; FIG. 6 is a right side elevational view of the LED housing; FIG. 7 is a top plan view of the LED housing; and, FIG. 8 is a bottom plan view of the LED housing.

The broken lines depict portions of the LED housing in which the design is embodied and form no part of the claimed design.

1 Claim, 7 Drawing Sheets(56)
